(57) **CLAIM**

The ornamental design for a candle and container, as shown and described.

DESCRIPTION

FIG. 1 is a perspective view of a candle and container.

FIG. 2 is a front view of the candle and container of FIG. 1.

FIG. 3 is a rear view of the candle and container of FIG. 1.

FIG. 4 is a left side view of the candle and container of FIG. 1.

FIG. 5 is a right side view of the candle and container of FIG. 1.

FIG. 6 is a top view of the candle and container of FIG. 1.

FIG. 7 is a bottom view of the candle and container of FIG. 1.

FIG. 8 is a perspective view of another embodiment of a candle and container.

FIG. 9 is a front view of the candle and container of FIG. 8.

FIG. 10 is a rear view of the candle and container of FIG. 8.

FIG. 11 is a left side view of the candle and container of FIG. 8.

FIG. 12 is a right side view of the candle and container of FIG. 8.

FIG. 13 is a top view of the candle and container of FIG. 8; and,

FIG. 14 is a bottom view of the candle and container of FIG. 8.

The broken line showing of environmental structure in FIGS. 1-14 is for illustrative purposes only and forms no part of the claimed design.
